UNITED STATES PATENT OFFICE

SEELEY C. GULICK, OF CHAMPAIGN, ILLINOIS

OIL BURNER AND SIMILAR FUEL-CONSUMING MEANS AND SYSTEM THEREFOR

Application filed March 10, 1928. Serial No. 260,762.

This invention relates to oil burners and similar fuel consuming means and is particularly adapted for use with the system described in my copending application filed July 12th, 1928, Serial No. 292,310, which application is a division of the present application as originally filed.

An important object of the invention is to provide a novel type of fuel oil burner where-in the oil and primary air are supplied under pressure in a novel manner to be perfectly burned at the nozzle.

A further object is to provide a novel burner including a body having a burner nozzle at one end thereof, and to provide novel means for supplying fuel and primary air to said body for combustion at the nozzle thereof.

A further object is to provide a device of the above mentioned character wherein two sources of primary air are provided from the nozzle, one source of air being adapted to mix air with the fuel prior to its ejection through the nozzle, while the other source of primary air is adapted to supply air under pressure to the air and fuel previously mixed, at its point of ejection through the nozzle.

Other objects and advantages of the invention will become apparent during the course of the following description.

In the drawings I have shown one embodiment of the invention. In this showing,

Figure 1 is a plan view of the burner and associated elements, parts being shown in section,

Figure 2 is a rear elevation of the same, parts being broken away,

Figure 3 is a detail section on line 3-3 of Figure 1.

Referring to the drawings, the numeral 10 designates a burner as a whole including a substantially cylindrical body 11 having lateral projections 12 and 13 on opposite sides

similar projection 14 is carried by the lower side of the burner body as shown in Figure 2.

The body of the burner is provided with parallel passages 15 and 16 communicating respectively with ports 17 and 18 formed in the projections 12 and 13. Pipes 19 and 20, connected respectively to sources of fuel oil and air supply, communicate with the ports 17 and 18, as clearly shown in Figure 1. Similarly, an air pipe 21 is connected to the projection 14 to supply air to a passage 22 arranged in the body of the burner, substantially axially thereof.

Valve stems 23 and 24 are arranged respectively in the passages 15 and 16 and each is provided with an enlarged threaded portion 25 received in threaded openings 26 formed in the outer portion of the body. Beyond the threaded portions, the valve stems extend through packing members 27 maintained in position by sleeves 28. These sleeves are arranged adjacent each other, as will be obvious, and are adapted to be secured in position by engagement with the head of a screw 29, as shown in Figure 1. The sleeves 28 and their associated packing members are preferably slidable in the body of the burner and are readily removable by removing the screw 29 and rotating the valve stems to withdraw the latter. Each valve stem is provided with a preferably knurled head 30.

The burner proper comprises inner and outer axial nozzle members 31 and 32 having substantially hemispherical inner ends, as shown in Figure 1. The inner nozzle member has its outer face seated against the inner end of the burner body while the outer nozzle member is threaded on the body and on the inner end of the inner nozzle member. The two nozzle members are spaced from each other to provide an annular space 33 and each is provided with a nozzle opening 34. The inner nozzle member is provided with a pair of passages 35 and 36 communicating

respectively with the passages 15 and 16. The outer ends of these passages deliver oil and air to a pocket 37 formed in the inner end portion of the inner nozzle and communicating with the inner nozzle opening 34. The inner nozzle member also is provided with a passage 38 communicating with the axial passage 22 of the burner body, and the outer end of the passage 38 communicates with a transverse passage 39 (see Figure 3) to deliver air to the annular space 33.

The inner ends of the valve stems 23 and 24 are provided respectively with valves 40 and 41 to control communication between the passages 15 and 16, and the passages 35 and 36. Means to be described is provided for controlling the passage of air into the annular space 33 through the passages 22, 38 and 39.

20 A combined supply and supporting member 42 is arranged outwardly of the burner and is preferably formed as a single casting. The member 42 is provided at opposite ends with aligned portions 43 and 44 respectively 25 provided with axial passages 45 and 46. The member 42 is further provided with an offset portion 47 for a purpose to be described. The passages 45 and 46 are provided with lateral extensions 48 and 49 respectively communicating with the pipes 20 and 19, these pipes obviously being secured to the member 42 and forming therewith substantially a unit construction.

25 Adjacent its inner end, the interior of the portion 43 of the member 42 is provided with a wall 50 having an opening therethrough. This opening is provided with a valve seat 51 adapted to be engaged by a valve 52 carried by a stem 53. This stem is threaded in a plug 54 which, in turn, is threaded in the inner end of the portion 43 of the support, and the free end of the stem 53 is provided with a preferably knurled operating knob 55. It will be obvious that space for the knob 55 and associated elements is provided by offsetting the intermediate portion 47 of the member 42. The space between the wall 50 and plug 54 forms a chamber 56 adapted to receive air from the passage 45 when the valve 52 is open, and the chamber 56 communicates with a passage 57, as shown in Figure 1. The pipe 21 is connected to the supporting member 42 and communicates with the passage 57. The valve 52 obviously constitutes the means for controlling the passage of air into the pipe 21, and consequently to the annular passage 33 in the burner nozzle.

30 The outer ends of the supporting member 42 are ground to provide conical seats 58 adapted to be engaged by corresponding conical projections 59 carried by supports 60. These supports are provided with passages 61 and 62 communicating respectively with the passages 45 and 46. The outer ends of

the passages 61 and 62 turn downwardly as at 63 for communication with air and oil supply pipes respectively, the supply pipes being secured to the supports to fix the latter in position. Each of the supports 60 is provided with an ear 66 having openings for the reception of a tie rod 67. This rod is provided at one end with a head 68 engaging the outer face of one of the ears 66, and at its outer end with a nut 69 by means of which the supports may be drawn toward each other. It will be apparent that tightening of the nut 69 causes the conical faces of the supports to tightly engage the conical seats 58 to provide leak-proof joints and to support the burner and associated elements in position. By loosening the nut 69, the supports 60 can be sprung apart to permit the burner and associated parts to be removed as a unit.

35 The operation of the burner will be clear from an examination of the figures. Oil and air under pressure from sources not shown will be supplied to the members 60 through the supply pipes. Preferably the oil and air is supplied by means of the apparatus described in my aforementioned copending application. Oil flows into the passage 46 of the member 42, to be supplied to the burner through pipe 19. Similarly, air will be supplied to the passage 45, and thence to the burner through pipes 20 and 21. From the pipe 19, the oil flows through port 17 into passage 15, and thence through passage 35 into chamber 37. Similarly air flows from the pipe 20 through port 18, thence through 40 passages 16 and 36 to the chamber 37. The oil and air escape orifices leading into the chamber 37 are relatively small, and since the air and oil are supplied under pressure, an efficient mixing action will take place when they are brought together in the chamber 37.

45 In this connection it will be noted that the outlet end of the passage 36, leading into the chamber 37, is arranged substantially axially, while the outlet end of the passage 35 is inclined to direct the escaping stream of oil into the path of travel of the air. This construction assists in providing an efficient oil and air mixture, and from the chamber 37, the mixture is projected through the burner orifices 34. As previously described, air is admitted into the annular chamber 33 through passages 22 and 38, and through the transverse passage 39, as shown in Figure 3. It will be apparent that the space between the inner and outer nozzle members 31 and 32 at the orifices 34 is restricted, and accordingly air will be delivered at a high velocity to the outer orifice 34 to be discharged therefrom. This air mingles with the air and fuel mixture from the chamber 37, which is in an atomized condition, and assists in discharging it from the nozzle at high velocity to completely vaporize the fuel mixture.

50 Thus a highly efficient mixture is provided 55

which burns cleanly and completely and furnishes the highest possible number of heat units per unit of fuel. The rate of flow of air and fuel, and the proportions thereof readily may be varied by operation of the valve nuts 30 and 55. The former provides for variations in the mixture in the chamber 37 while the latter varies the proportionate amount of air admitted into the annular 10 chamber 33.

It will be apparent that the burner, the pipes 19, 20 and 21, and the member 42 are connected together to form in effect a single burner unit, and the supporting means for 15 this unit permits its ready removal and replacement. In the event of the failure of the burner to operate for any reason, thus necessitating repairs to the burner, a duplicate burner unit readily may be installed 20 to prevent the necessity of stopping the operation of the apparatus until the repairs have been made. By removing the rod 67, the supports 60 may be sprung apart sufficiently at their upper ends to release the conical 25 engaging faces 58 and 59, whereupon the burner unit may be removed and a duplicate unit placed in position for continued operation of the apparatus. After the duplicate unit has been placed in position, the rod 67 30 is tightened in position, and the device is ready for operation. The conical engaging faces referred to are ground to provide leak-proof joints, as will be apparent.

It is to be understood that the form of 35 the invention herewith shown and described is to be taken as a preferred example of the same and that various changes in the shape, size and arrangement of parts may be resorted to without departing from the spirit 40 of the invention or the scope of the subjoined claim.

I claim:—

An oil burner comprising a body formed of two sections secured together, a third section arranged inwardly of and secured to 45 one of said first mentioned sections, a portion of said third section being spaced from its securing section to provide an air chamber therebetween, said chamber being provided with a discharge opening, said third section being arranged in abutting relation 50 with the other of said first mentioned sections and having a mixing chamber therein, the latter chamber being provided with a discharge opening in alignment with said first mentioned opening, said third member being provided with a fuel passage and 55 an air passage communicating with said mixing chamber, a pair of lateral extensions carried by the last named of said first mentioned sections, each extension being provided with a port communicating with one of said passages, a fuel pipe communicating 60 with one port, an air pipe communicating with the other port, said last mentioned sec-

tion being provided with a passage communicating at one end with said air chamber and at its opposite end with an inlet port, a pipe connected to said inlet port, and means for supplying fuel and air under 70 pressure to said pipes, the air supplied to said mixing chamber and said air chamber being delivered from a common source.

In testimony whereof I affix my signature.
